ELECTRICAL CONNECTOR HOUSING BLOCK

Joseph R. Keller, Harrisburg, Pa., assignor to
AMP Incorporated, Harrisburg, Pa.

Filed Sept. 10, 1962, Ser. No. 71,639

Term of patent 14 years

(Cl. D26—1)

FIGURE 1 is a perspective view of an electrical connector housing block;

FIGURE 2 is a top plan view of the device shown in FIGURE 1;

FIGURE 3 is an end view of the device shown in FIGURE 1; and

FIGURE 4 is a bottom view of the device shown in FIGURE 1.

I claim:

The ornamental design for an electrical connector housing block, as shown.
